UNITED STATES PATENT OFFICE.

CLIVE W. LANPHERE, OF NEW YORK, N. Y.

LOCK MECHANISM.

Application filed September 9, 1926. Serial No. 134,446.

The present invention relates to a lock having an interlocking bolt, a latch, and reversible elements making it adaptable to right and left hand doors.

More specifically the invention provides a locking mechanism comprising an arcuate bolt movable outwardly from a casing through a "strike" and into the casing, and a spring pressed latch to engage the strike.

The present construction is such that the bolt passes through a curved path and spans the gap between the door and the jamb at two different points spaced a relatively great distance apart, thus the bolt offers the same resistance to a direct force as would two individual locking bolts.

Because of the curved path through which the bolt travels it embraces a portion of the keeper making it exceptionally resistant to a separation of the bolt and keeper by means of a jemmy or other tool when inserted between the door and jamb as is often effective in attaining an opening of a door equipped with locks of the straight bolt type.

A lock of similar fundamental construction to the present invention is shown and described in my Patent No. 1,584,950, issued May 18, 1926. The lock herein shown and described embodies various improvements in the arrangement of the operative parts, and attains the desired result with a reduced number of movable elements. By reason of the various improvements the present lock may be more economically constructed and the parts are more readily and conveniently assembled making the article more practical from a manufacturing standpoint and salable at a price which gives the lock a wider range to a greater number of uses.

Briefly, the several improvements include the location of my cylinder outside the path of the bolt making it possible to reverse the cylinder, a latch and latch hubs therefor reversible, and a catch which renders the lock adaptable for use with a master key. Also, improved means for locking the bolt in its projected and retracted positions, and for releasing the same. Other improvements comprise a toothed segment and lever, also a double arm lever, which when oscillated by a knob causes the toothed members to throw or retract the bolt and retract the latch. A flanged guard is also provided to render sawing of the bolt difficult. The

above and other features will be more clearly understood by reference to the accompanying drawings in which:

Fig. 1 is a plan view of the inside of the lock the cover plate having been removed and showing the bolt retracted.

Fig. 2 is a view similar to Fig. 1 but with the bolt projected.

Fig. 3 is a view similar to Fig. 1 but shows several of the movable parts in different positions and illustrates the operation of the lock by a key lever on a key cylinder, the key cylinder being shown positioned in a threaded hole in the bottom wall of the casing and illustrating the reversibility of the lock.

Fig. 4 is a sectional view of the lock taken substantially on line IV—IV in Fig. 1 and shows the lock applied to a door.

Fig. 5 is a cross sectional view of the lock taken substantially on line V—V in Fig. 3.

Fig. 6 is a fragmentary enlarged view of the bolt and its relation to a keeper.

Fig. 7 is a detail view of a bolt locking detent.

Fig. 8 is an outside view of the lock showing a key cylinder on the cover plate.

Fig. 9 is a view of a knob for actuating the bolt.

Fig. 10 is a front view of a keeper.

Fig. 10^a is an end view of the keeper shown in Fig. 10.

Fig. 11 is a detail view of a latch.

Fig. 12 is a plan view of the latch.

Fig. 13 is a view of a toothed plate.

Fig. 14 is a spiral spring.

Fig. 15 is a view of a cam plate.

Fig. 16 is an end view of the cam plate, shown in Fig. 15.

The several parts shown in Figs. 13, 14 and 15 when assembled, constitute a bolt actuating unit.

Fig. 17 is a view of a part of my lock showing in detail, mechanism whereby the lock may be rendered inoperable except by the application of a master key.

Fig. 18 is a perspective view of a latch forming part of the mechanism shown in Fig. 17, and

Fig. 19 is a view taken substantially on line XIX—XIX in Fig. 17.

An embodiment of the present invention as shown in the preferred form is applied to a lock of the mortise type. It is, however,

obvious that the invention has equal utility when applied to a rim-type lock.

The selected construction of lock to illustrate the practicability of the invention may 5 include a housing or casing 20 comprised of a bottom wall 21 and side walls 22, 23, 24 and 25. The side wall 23 is extended at each end of the casing to provide a facing 26' and with extensions 26'' with screw holes for fastening 10 the lock to a door and a face plate 27 may be provided and secured to the facing by suitable screws. A cover plate 29 may complete the housing and may be fastened by suitable machine screws disposed in 15 tapped holes 31.

My lock mechanism may comprise cooperating elements which are primarily the same as those shown and described in my patent 20 above referred to, certain improvements to 20 the general construction having been made and greater simplicity of operation being attained.

As illustrated, the lock may comprise an 25 arcuate bolt 32 having a tongue 33 integral with an extended rear portion or tail-piece 34 and a fin or radius arm 35 having a hub 36 (see Figs. 5 and 6) journaled on a post or pivot pin 37. The post may be integral with the bottom wall 21 of the housing and 30 may be provided with a reduced portion which provides a supplemental pivot 38, the purpose of which will be later described. The arcuate bolt 32 is thus rotatable about the post 37 and may be oscillated by means 35 of a knob 39 (see Fig. 4) or a key 40 under the action of associated cooperating elements. The knob 39 may, as shown, be provided with a shank 41 extending through the woodwork 42 of a door 43' and into a 40 barrel member 44 carried in a disk member or insert piece 44' in which it is rotatable. The disk member is threaded and adapted to be screwed into a threaded aperture as provided for the key cylinder of a tumbler 45 type of key cylinder. As more fully hereinafter set forth, a key cylinder is disposed in the cover plate of the lock and in axial alignment with disk member 44'.

The free end of the shank 41 is disposed 50 in the barrel member 44 which may be provided with a double arm lever termed herein a knob-lever 45 associated with the knob in a manner to be later described (see Figs. 1 and 2). This knob-lever is provided with 55 two substantially radially disposed arms 46 and 47 positioned for engagement with an arm 48 of a bell-crank member or gear segment lever 49. A reversible stop screw pin 50 disposed on the disk member 44' is provided 60 to limit the movement of the knob-lever 45 which prevents it retracting the latch. The stop pin 50 may, as shown, be positioned to engage one side of double arm lever 45 or the pin may be positioned in the 65 threaded aperture 50' to engage the opposite

side of the said lever. Thus the pin may act as a stop when the lock is reversed.

The opposite arm 51 of the gear segment lever is provided with a toothed segment 52. The gear segment lever 49 is movable on a 70 pivot 53 fastened to the bottom plate 21 of the housing 20. The segment 52 is disposed in mesh with a toothed portion 54 of a disk 55. This disk is fastened to a plate or what may be termed a bolt-cam-plate 56 which, as 75 shown in Figs. 13, 15 and 16, is provided with raised portions 57, 58 and 59. The portions 57 and 58 extend laterally from the plate and serve as cam members for purposes to be presently set forth. Each of the 80 raised portions has a tapped hole 61 whereby the disk 55 may be secured thereto by screws extending through suitably disposed holes 62 in the disk. Before the disk 55 and plate 56 are secured together a spiral spring 85 63 is disposed between them; the inner end of the spring being secured in a slot 64 formed in a flange 65 at the perimeter of a centrally located circular aperture 66 in the plate 56. The disk 55 and plate 56 with 90 the spiral spring therebetween may be disposed for rotation about the supplemental pivot 38, the aperture 66 being of such dimension as to provide a running fit for the 95 united elements which as a whole, may be termed an intermediate bolt and latch actuating unit. This unit, as shown in Fig. 5 when in position upon the pivot 38, is located above the hub of the arcuate bolt 32 and the free or opposite end 67 of the spiral 100 spring 63 may be secured in a slot 68 provided in a lug 69 integral with the fin 35 of the bolt 32 (see Fig. 6). When the bolt actuating unit is in its proper position with relation to the bolt, the lug 69 is disposed 105 at one side of the edge of the plate 56 and between the projecting cam members 57 and 58. The action of the spiral spring 63 when secured to the bolt is to cause a movement of the bolt actuating unit in the direction of the arrow "X" when the bolt is in its retracted position. This action of the spring causes the gear segment 54 of the disk 55 to move the gear segment 52 which takes the position shown in Fig. 1. The projection 57 of the plate 56 then engages with the lug 69 on bolt 32 and serves as a stop, when the key 40 is released after a retraction of the bolt and latch. When the bolt 32 is in its retracted position as shown in Figs. 1 110 and 3 a locking detent 70 pivoted at 70' operates under the action of a spring 71' to enter a notch 72' in the bolt 32 and thus hold the same in its retracted position. The detent may, however, be disengaged from the 115 bolt by a movement of the knob lever 45 which engages with a cam surface 73' at one end of the detent.

For the purpose of automatically actuating the double arm lever 45 to clear the 120

detent and permit it to engage the bolt 70 a spiral spring 70" is provided having one end secured at the center of rotation of the lever 45 and the opposite end secured in a slot in a suitably positioned lug 70". Moving the arms 45 or 71 toward the surface 84' of the bell crank 48 disengages the detent 70 and permits projecting the bolt.

An actuation of the bolt by turning the key 40 may be effected by means of a cam arm 71 fastened to the inner side of a key barrel 72 of any suitable type of key cylinder lock 74 (see Fig. 4) extending through the woodwork of door 43' upon the side opposite to the knob 39. The cam arm 71 and the knob lever 45 are so disposed as to be rotatable about a common axis. The key cylinder may be screwed into the cover plate 29 of the housing 20 and in alignment with the disk member 44' as above mentioned.

Two pairs of screw rods 75 and 76, shown in Fig. 1, and 75' and 76' in Fig. 4, prevent rotation of the key cylinder by a wrench or other tool and afford the adaptation of the key cylinder to either side of the lock, making it reversible. The disk member 44' and the key cylinder 74 are thus interchangeable as the cylinder 74 is provided with notches 74' and the disk member with notches 74" to receive the screw rods. The free ends of the rods 75 and 76 and 75' and 76' may extend to the facing 26 of the casing and are accessible to be screwed in place after which the face plate 27 may be fastened in place. It will be evident that by means of the rods 75 and 76 and 75' and 76' which lock the key cylinder in place, the force required to move it would be greater than attainable by the use of a tool. Any attempt to turn the cylinder will be opposed by a direct thrust against one rod and across the other.

I may further insure against a manipulation of the cylinder by providing escutcheon plates 77 and 78 shown in Fig. 4 and having the plate 77 of such thickness that the end 79 of the key cylinder which projects from the wood of the door will be flush with the surface of the plate, thus preventing the application of a tool to the cylinder. The plates 77 and 78 may be secured by bolts 81 and 82 extending through the door and plates the nuts 83 of the bolts being on the inner side of the door.

Referring again to the lock mechanism it will be noted that the cam arm 71 operates, when the key 40 is turned to engage with surface 84 of the arm 48 of the gear segment 49 to retract the bolt 32 and the surface 84' to project it.

If the bolt 32 is to be projected an initial or partial rotation of either the key or knob causes the gear segment 49 to be oscillated, causing a rotary movement of the bolt actuating unit to move the projecting portion 57 of the plate 56 which is in contact with the

lug 69 on the bolt. A continued movement of either the knob or key results in the projection of the bolt.

When projected, the bolt is locked against return movement by means other than the knob 39 or key 41. The means for locking the bolt may comprise a locking pawl 85 movable on a pivot 80 having a projection 86 to engage with a tooth or lip 87 integral with the hub 36 of the bolt 32 (see Fig. 6). The locking pawl is normally moved to locking position by a spring 88. The projection 86 of the pawl is thus pressed against the outer surface of the hub 36 and traverses the same until it rides over the tooth 87 at which time the bolt is wholly projected.

The pawl 85 must, however, be lifted to permit a retraction of the bolt and in the present construction this can only be accomplished by a movement of the bolt actuating unit and consequently only by a partial rotation of the knob 39 or key 41. The pawl 85 is therefore formed with a concave surface 89 so as to provide a greater distance between the pawl and hub 36 adjacent to the projection 86 than between the free end 91 of the pawl and the hub. This space or clearance permits the cam member 58 to take a position close to the projection 86 when the bolt is projected and to engage with the end 91 of the pawl as the plate 56 moves under the action of the knob or key. The movement of the plate 56 results in an engagement between the member 58 and the pawl 85 to lift the latter, as shown in Fig. 7 and release the bolt for retraction. The necessary initial movement of the bolt actuating unit comprising the plate 56 is provided for since the said unit is free to move independently of the bolt until the projecting portion or cam member 58 engages the lug 69 of the bolt, this contact occurring after a partial movement of the knob or key which carries the bolt along to its retracted position.

In addition to the bolt 32 it is, of course, desirable to provide the lock with a latch for general use and particularly to hold the door closed when the bolt is not locked. Any suitable latch mechanism may be employed. The mechanism shown includes a latch bar 92 having a beveled end 93 normally projecting from the casing under the action of a helical spring 94 positioned between the beveled end 92 and a guide 95. The latch bar 92 has an extension 96 terminating in an offset portion 97 to engage a nose piece 98 on a yoke 99. The yoke is constructed with an arm 101 adapted to rock upon a fulcrum 102 and is held under tension by engagement with an end of a spring 103. The yoke 99 is disposed about a hub 104 having a rectangular aperture 105 to receive a spindle for knobs 106 at opposite sides of a door in the usual manner. The hub 104 is provided

with a lever arm 104" normally in engagement with the nose piece 98 of the yoke 99. Thus when a knob 106 is turned in either direction to move the latch inwardly the nose piece effects a movement of the yoke in opposition to springs 94 and 103.

It is desirable, however, to effect an automatic retraction of the latch when the bolt 32 is retracted by the key. The latch therefore is associated with the lock actuating unit by a rocker bar or lever 107', one arm of which is disposed in a slot 108 in the latch 92 (Figs. 11 and 12). The opposite end 113 of the lever is positioned to be engaged by the cam member 57 of the plate 56 on the bolt actuating unit. When the bolt 32 is retracted by the key, the cam member 57 engages the lever end 113 and the latch is retracted during the final movement of the key. When the key is returned to its initial position the cam member 57, under the action of the spring 63, will return to its contact with lug 69 on the bolt 32 and the latch 92, under the action of the spring 94, will be projected and disposed in a suitable aperture 109 of a keeper 110 having the necessary apertures 111 and 112 for the reception of the bolt 32.

It will be noted that in the present construction the latch 92 is reversible and provided with slots 108 on both sides thereof to receive the lever 107' in either a right or left hand lock thereby avoiding separate latch bars for each condition. For the purpose of holding the latch 92 inoperable I may provide the usual push button stop 115 and releaser 114 movable through suitable apertures in the wall 23 and the face plate 27 of the lock and associated by a pivoted member 116.

The push button 115 may be provided with an extension 117 (see Fig. 2) arranged to have an end 118 thereof inserted into a notch 119 formed in the lever arm 104" of the latch hub 104. When the end 118 is disposed in the notch the latch hub will be held immovable and may be released by pressing the push button 114. A second latch hub 104' is loosely connected by a collar (not shown) to the hub 104. Their positions are interchangeable in the usual manner.

The keeper or strike 110 (see Fig. 10) sometimes termed a guard or striking plate into which the bolt 32 is projected may be similar to that set forth in the above mentioned patent, however, I have added a longitudinal flange 121 and as will be noted, apertures 109 and 109' are similar and provide for a reversal of the keeper, thus if the keeper is reversed by reason of a right or left hand door, a suitably located aperture will be provided for the latch 92.

The present construction of lock is adapted to be provided with means which may be

manipulated from the inside of the door to lock the bolt in its projected position making it impossible to unlock the door from the outside by means of the usual key, but permitting the door to be unlocked when a master key is employed. This construction is found desirable when the lock is used on the doors of rooms of hotels or the like so that the occupant may lock the door from intrusion except in the case of an emergency. An authorized person with the proper master key may render ineffective the manually applied catch and open the door.

When providing my lock with means as just described I may utilize a key cylinder 126 of the type shown in Figs. 17 and 19 having a plug and sleeve. This cylinder has the usual tumblers 127 which may be moved by a key 128 to permit a rotation of the key plug 129 causing a movement of the lever arm 130 to actuate the gear lever 49. A second lever arm 131 is, however, provided with this type of key cylinder which lever arm is movable with a sleeve 132. The sleeve is only movable, however, when the tumblers are actuated by a master key. This action is due to the fact that the ordinary key merely moves the tumblers to the division line 133 between the key plug 129 and sleeve 132 while the master key moves the tumblers to 95 the dividing line 134 between the cylinder 126 and the sleeve 132.

Means for locking the gear lever 49 may comprise a U-shaped catch 135 as shown more clearly in Fig. 18 movable between a guide-piece 136 integral with the casing of the lock and a guide piece 137 integral with the cover plate of the lock casing. The catch 135 may be provided with a finger piece 138 disposed upon an escutcheon plate 139 of the lock 105 and the catch may thus be manipulated to engage a stud 140 secured to the lever arm of the gear lever 49.

When the catch is engaged with the stud 140 the bolt is in its projected position and it will be evident that the bolt can not be moved except by means of the master key as the catch is so shaped that the arm 130 can not strike it. When such key is applied to the lock the sleeve may be rotated 115 and the arm 131 caused to engage with an end 141 of the catch causing the catch to be moved and disengaged from the stud 140. A continued movement of the key causes an actuation of the gear lever and a retraction of the bolt and latch in the above described manner since the key cylinder 126 is provided with lever arms 130 and 131 which will engage the arm 48 of the gear or bell crank lever in a manner hereinbefore described.

It will be appreciated that with the present construction a key cylinder may be used on both sides or may be integral with the casing as when the wall of the case extends to the surface of the door.

Although a preferred embodiment of the invention is shown and described herein it is to be understood that modifications may be made therein without departing from the spirit and scope of the invention as set forth in the appended claims.

What is claimed is:

1. A lock comprising a casing, a guard, a bolt adapted to interlock with said guard, a spindle means to actuate said bolt from one side of said casing, key-actuated means to actuate said bolt from another side of said casing, and means to permit interchanging the positions of said spindle and said key-actuated means.
2. A lock comprising a casing, a guard, a bolt adapted to interlock with said guard, a spindle means to actuate said bolt from one side of said casing, a cylinder lock to actuate said bolt from another side of said casing, means to permit interchanging the positions of said spindle and said cylinder lock, and a latch.
3. A lock comprising a casing, a guard, a bolt adapted to interlock with said guard, a reversible latch and interchangeable means to actuate said bolt and latch.
4. A lock comprising a casing, lock mechanism supported by said casing, reversible means to operate said lock mechanism, and means offset with respect to the center of said reversible means for securing the latter to said casing.
5. A lock comprising a casing, a bolt movable in said casing, and a flanged guard engageable by said bolt, said flange projecting toward said casing.
6. A lock comprising a casing, an interlocking bolt supported by said casing, key-controlled means to actuate said bolt, manually actuated means to render said key-controlled means inoperative, said key-controlled means being adapted to release said second-mentioned means.
7. A lock comprising a casing, an interlocking bolt supported by said casing, and a reversible striking plate or guard cooperating with said bolt.
8. In combination with a striking plate, a lock comprising a bolt movable in a curved path, a latch engageable with said striking plate, means for actuating said bolt and latch, said means being partially disposed outside of the path of movement of said bolt, and a cylinder lock, said cylinder lock having a detached connection with said actuating means.
9. A lock comprising a bolt movable in a curved path, bolt cooperating means, a strike having a plurality of apertures to engage said bolt, said means including actuation means disposed outside of the path of the bolt, said actuation means having a detached connection with its cooperating means.

10. A lock comprising a casing, a guard, a bolt adapted to interlock with said guard, a latch, spindle means to actuate said bolt and latch from one side of said casing, key operated means to actuate said bolt and latch from another side of said casing, and means to permit interchanging the positions of said spindle means and said key operated means.

11. A lock comprising a bolt, a detachable gear to actuate said bolt, and a gear lever to actuate said gear.

12. A lock comprising a pivotal bolt having a radius arm offset with respect to itself and plural interchangeable means to actuate said bolt.

13. A lock comprising a casing, a bolt disposed in said casing, mechanism for operating said bolt, an insert piece having means to permit actuation of said bolt operating mechanism, and a plurality of means to hold said insert piece in fixed position.

14. A lock comprising a casing, an interlocking bolt supported by said casing, a guard with which said bolt is adapted to interlock, a lever cooperating with said bolt and means including a lost motion bifurcated cam for operating said lever.

15. A lock comprising a casing, an interlocking bolt, a guard adapted to cooperate with said bolt, mechanism including a cylinder lock to operate said bolt, said casing being adapted to receive said cylinder lock in either one of two positions.

16. A lock comprising a casing, a guard, a bolt adapted to interlock with said guard, operating means including means to actuate said bolt from one side of said casing, means for actuating said bolt from another side of said casing, and means to permit interchanging the positions of said actuating means.

17. A lock comprising a casing, a curved bolt supported by said casing, and interchangeable operating means for said bolt, whereby said lock is adaptable to right or left hand doors.

18. A lock comprising a casing, a curved bolt supported by said casing, a latch having a beveled surface, means to adapt said latch to right or left hand doors by turning said beveled surface to face in an opposite direction, actuating means for said latch and said bolt and plural independent actuating means for said latch.

19. A lock comprising a casing, a curved bolt supported by said casing, operating mechanism for actuating said bolt, said operating mechanism including interchangeable elements for adapting the lock to right and left hand doors.

20. A lock comprising a casing, a curved bolt supported by said casing, and a latch, and interchangeable actuating means for said bolt and latch.

110

115

120

125

130

21. A lock comprising a casing, an arc bolt, a latch, and common operating means including a plurality of levers, for actuating said bolt and an additional lever for actuating said latch.
22. In combination with a striking plate, a lock comprising a casing, a bolt mounted in said casing and movable in a curved path, into and out of said casing, a latch bolt engageable with said striking plate, operating means for said first mentioned bolt, operating means for said latch bolt, a cylinder lock carried by said casing, and having a plug extending into said casing, said cylinder lock being disposed outside of the path of movement of said bolt and adapted to actuate said bolt and latch bolt operating means.
23. A lock comprising a casing, a key-controlled pin tumbler, a guard, a bolt adapted to interlock with said guard, means to actuate said bolt from one side of said casing, means for actuating said bolt from another side of said casing, and means to permit interchanging the positions of said respective means.
24. A lock comprising a casing, a bolt movable in a curved path, a latch, common means to operate said bolt and latch, manual independent means to retract said latch, and means actuated from within the path of said bolt to render said latch retracting means ineffective.
25. A lock comprising a bolt movable in a curved path, operating means for said bolt including pin tumbler-actuating mechanism for said bolt disposed outside of the path of movement of said bolt, plural means off-center to said mechanism to hold said mechanism against movement.
26. A lock comprising a casing, a pivotal bolt, a latch bolt, means to operate said pivotal bolt and latch bolt from one side of said casing, and means to operate said pivotal bolt without operating said latch bolt from the other side of said casing.
27. A lock comprising a casing, a pivotal bolt, means to project said bolt, automatic means to hold the bolt locked when in projected position, a latch bolt, a plurality of levers to operate said bolts and key-operated mechanism carried by said casing to operate said levers.
28. A lock comprising a casing, a pivotal bolt, a latch, bolt projection means, automatic means to lock the bolt when in its projected position, a plurality of levers to operate said bolt, key operated mechanism to operate the levers, and means to operate said latch.
29. A lock comprising a casing, a pivotal bolt, means to project said bolt, automatic means to hold said bolt when in its projected position, a latch, and a plurality of levers to retract the bolt and latch.
30. A lock comprising a casing, a bolt movable in a curved path, manual means to hold said bolt inoperative, and a cylinder lock having a plurality of levers, one lever adapted to release said manual holding means.
31. A lock comprising a casing, a pivotal bolt, a latch bolt, operating means for said bolt, key-controlled means to actuate said operating means, and a knob to actuate said bolt operating means without actuating said latch bolt.
32. A lock comprising a casing, a pivotal bolt, a latch bolt, operating means for said bolts, key-controlled means to actuate said operating means, a knob to actuate said bolt operating means without actuating said latch bolt, and an additional operating means and a knob to retract said latch bolt.
33. A lock comprising a casing, a pivotal bolt, a latch bolt, means to operate said pivotal bolt, means to operate said latch bolt, common means cooperating with each of said bolt operating means to actuate the same, manual independent means to retract said latch bolt, and means including a lever to hold said manual means inoperable.
34. A lock comprising a casing, a pivotal bolt, a latch bolt, means to operate said pivotal bolt, means to lock said pivotal bolt in a fixed position, means to operate said latch bolt, common means cooperating with each of said bolt operating means to actuate the same, manual independent means to retract said latch bolt, and means including a lever to hold said manual means inoperable.

In testimony whereof I affix my signature.
CLIVE W. LANPHERE.
